UNITED STATES PATENT OFFICE.

MARTIN H. COLLOM, OF IDAHO SPRINGS, COLORADO.

BED-SPRING.

SPECIFICATION forming part of Letters Patent No. 374,658, dated December 13, 1887.

Application filed September 6, 1887. Serial No. 248,945. (No model.)

To all whom it may concern:

Be it known that I, MARTIN H. COLLOM, a citizen of the United States, residing at Idaho Springs, in the county of Clear Creek and State of Colorado, have invented certain new and useful Improvements in Bed-Springs; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 This invention relates to an improved spring and bed-bottom of springs.

Heretofore it has been customary to make coil-springs out of a single wire formed into a single coil, or to have the wire bent near its middle and each half made into a spring the convolutes of which are concentric and parallel or oppositely disposed relative to each other, thus making what is called a "double spring." Such springs, when arranged in series to form a bed-bottom, have the cross-wires which connect the springs and form the supporting-surface for the bed-clothing attached directly to the springs by being twisted about the same, or connected therewith by 30 links, loops, or equivalent devices.

This invention aims to obviate the above objections and produce a spring which will do away with all sharp points and dispense with all ties or bands for connecting the springs 35 to each other and to the cross-wires.

The improvement consists in a spring made of a single wire doubled on itself and having its limbs twisted together. The wire thus twisted is formed into a coil-spring. A series 40 of such springs arranged to form a bed or other bottom are connected together by cross-wires passed between the strands of the convolutes of the springs.

The improvement further consists in the 45 novel features more fully hereinafter set forth, claimed, and shown in the annexed drawings, in which—

Figure 1 is a perspective view of a spring embodying my invention, and Fig. 2 a plan view of a spring bed-bottom of my invention.

The spring A is made of a single wire bent

at its middle to form two limbs or strands, which are twisted together and formed into desired shape. It is preferred to have the spring made of a single wire bent at its middle, as thereby no ends are formed to catch into and tear the bed-clothing; but the spring may be formed of two wires or strands twisted together, as shown by the dotted lines in Fig. 1. A number of springs constructed as above 55 described and arranged in a series to form a bed-bottom, as shown by Fig. 2, are connected together by the cross-wires B, which pass diagonally across the springs and between the strands of their twists and through the eyes 60 formed at the ends of the springs by the bend in the wires composing them. The cross-wires intersect with the springs at four points and hold their upper convolutes in the same plane, thus rendering it impossible for the 65 springs to tip. By this construction a network is formed across the spaces between the springs and a larger number of the springs are brought into action at one time.

Having thus described my invention, what I 75 claim, and desire to secure by Letters Patent, is—

1. A coil-spring composed of two strands twisted together, substantially as and for the purpose described.
2. A coil-spring formed of a single wire doubled or bent at its middle to form two limbs, which are twisted together, substantially as specified.
3. A bottom composed of a series of springs 85 formed of twisted strands and the cross-wires passed between the strands of a twist for connecting the springs together.
4. A spring-bottom composed of a series of springs made of wires, bent at their middle to 90 form an eye, and two strands, which strands are twisted together, and the cross-wires passed through said eyes and between the strands of a twist of the springs for connecting them together, substantially as and for the 95 purpose specified.

In testimony whereof I affix my signature in presence of two witnesses.

MARTIN H. COLLOM.
